[57] **CLAIM**

The ornamental design for a door for a computer disk drive, as shown and described.

DESCRIPTION

FIG. 1 is an isometric view of a door for a computer disk drive showing our new design;

FIG. 2 is a top plan view thereof;

FIG. 3 is a bottom plan view thereof;

FIG. 4 is a side view thereof;

FIG. 5 is an opposite side view thereof;

FIG. 6 is a back end view thereof; and,

FIG. 7 is a front end view thereof.

The broken lines are in the views for illustrative purposes only and form no part of the claimed design.
